The figure is a perspective view as seen from above and one side of a cigarette lighter embodying my new design.

The surface texture is partially shown on the switch and casing for convenience of illustration, it being understood that the toothed rows are uniformly continuous over the switch and that the fluting is uniformly continuous on the front, rear, and sides of the casing. The top of the lighter, which is stipple-shaded, is of a contrasting color.

I claim:

The ornamental design for a cigarette lighter, as shown and described.
